UNITED STATES PATENT OFFICE

ERNST KATZ, OF VIENNA, AUSTRIA

LOOSE-LEAD-PENCIL HOLDER

Application filed October 17, 1928, Serial No. 313,067, and in Austria April 12, 1928.

This invention relates to improvements in loose lead pencil holders the lead-tube of which is slidable or adjustable within the clamping sleeve or head and is automatically charged with a new lead from a receptacle, connected with the lead-tube by a funnel-shaped member and containing a supply of leads.

The essential feature of the present invention consists in that the lead is clamped by the head of the pencil, and the clamped lead is fed forward by a rotary member or knob. A particular advantage of the construction according to the present invention resides in the combination of a pencil with automatic feed with a loose lead pencil holder, in which a large number of leads can be stored.

One mode of carrying out the present invention is illustrated by way of example on the accompanying sheets of drawings, in which—

Figures 1, 2 and 3 show in sectional elevation one embodiment of the invention; Figure 4 is a cross-section view, the section being taken on line $a-b$ of Figure 1.

In the embodiment shown in Figs. 1 to 4, the forward end of the barrel 1 is provided with an inner screw-thread into which is screwed the head or mouth-piece 2 of the loose lead pencil holder, the bore of the same being of particular shape. The top portion of the same is shaped as clamping sleeve 3^a, while the diameter of the bottom portion of the bore 3^b corresponds to the diameter of the lead.

The lead-tube 4 is slotted at 4^a and, within the enlarged cylindric part 3^c of the bore 3, is connected with the cylindric tube 8 by a conical shaped or funnel-shaped member 7. The rear end of the tube 8 is provided with a left-handed thread, which is engaged by a corresponding thread of the tube 10, which is reduced in diameter 9 and together with the tube 8 forms the lead storage compartment 11.

If it is desired to insert a new lead from the storage compartment into the lead-tube 4 or to push forward a lead, the head or mouth-piece 2 is slightly screwed out of the barrel 1, as shown in Fig. 1, so that the lead-tube 4

and the lead are not subjected to any clamping action. Now the lead in the lead-tube or a new lead from the storage compartment 11 drops forward. This procedure is shown in Fig. 1. Now the head 2 is screwed into the barrel 1, so that the lead-tube 4 is clamped again, as shown in Fig. 2.

Hereafter the handle 13 is turned to the left and, owing to the screw-threaded engagement between the tubes 8 and 10, the tube 8 as well as the lead-tube 4 and the clamped lead are moved forward solely in an axial direction, so that the lead projects out of the head 2. The rotation of the pipe 8 is prevented by the cooperation between two projections 1^a, 1^b and the longitudinal grooves 8^a, 8^b. Fig. 5 illustrates the loose lead pencil holder in the position ready for writing.

What I claim is—

1. Loose lead pencil holder comprising in combination a barrel, a lead-tube slotted at one end and arranged within the same, a clamping head screwed to the barrel for clamping the lead in the slotted end of the said lead-tube, a lead storage compartment consisting of two parts, a funnel-shaped member connecting the bottom part of the said compartment with the lead-tube, means for rotating the top part of the said compartment and securing the same against axial movement, and means for transforming the rotary motion of the said top part into an axial movement of the said bottom part.

2. Loose lead pencil holder comprising in combination a barrel, a lead-tube slotted at one end and arranged within the same, a clamping head screwed to the barrel for clamping the lead in the slotted end of the said lead-tube, a lead storage compartment consisting of two parts, a funnel-shaped member connecting the bottom part of the said compartment with the lead-tube, means for rotating the top part of the said compartment and securing the same against axial movement, a screw-thread on the top part and a screw-thread on the bottom part cooperating with the screw-thread first mentioned for transforming the rotary motion of the top part into an axial movement of the bottom part.

3. Loose lead pencil holder comprising in combination a barrel, a slotted lead-tube arranged within the same, a clamping head screwed to the barrel and provided with 5 a funnel-shaped bore for clamping the lead in the slotted lead-tube and with an adjoining cylindric bore, a lead storage compartment with a discharge opening tapering off towards the lead-tube, and means for axially 10 displacing in the cylindric bore the said storage compartment and the adjoining clamped lead-tube.

4. Loose lead pencil holder comprising in combination a barrel, a lead-tube slotted at 15 one end and arranged within the same, a clamping head screwed to the barrel for clamping the lead in the slotted end of the said lead-tube, a lead storage compartment consisting of two parts, a funnel-shaped 20 member connecting the bottom part of the said compartment with the lead-tube, means for rotating the top part of the said compartment and securing the same against axial movement, and means for transforming the 25 rotary motion of the said top part into an axial movement of the said bottom part and for preventing a rotation of the latter.

In testimony whereof I affix my signature:
ERNST KATZ.
